UNITED STATES PATENT OFFICE.

MORGAN BARNEY, OF NEW ROCHELLE, NEW YORK.

MOTOR BOAT OR YACHT.

1,123,068.

Specification of Letters Patent.

Patented Dec. 29, 1914.

Application filed October 17, 1914. Serial No. 867,072.

To all whom it may concern:

Be it known that I, MORGAN BARNEY, a citizen of the United States, residing at New Rochelle, county of Westchester, State of New York, have invented a certain new and useful Motor Boat or Yacht, of which the following is a specification.

This invention relates to improvements in motor boats or yachts of the cruiser type and has for its objects: First: To secure as much available living space as possible on a given length. Second: To isolate the engine room and at the same time render it well ventilated and suitable for berthing the professional crew. Third: To provide access to the cabin directly from the bridge deck, but without intruding the accommodation ladder into the cabin. These and further objects will more fully appear from the following specification and accompanying drawings, considered together or separately.

In the drawings, Figure 1 is a deck plan of the entire boat; Fig. 2 is a below deck plan; Fig. 3 is a section taken on the line 3—3 of Fig. 2; Fig. 4 is a similar view taken on the line 4—4 of Fig. 2; Fig. 5 is a deck plan of the midship portion of the vessel; Fig. 6 is a section on the line 6—6 of both Figs. 3 and 4; Fig. 7 is a section on the line 7—7 of Fig. 6; Fig. 8 is a section on the line 8—8 of Fig. 6; and Fig. 9 is a detail of a modification. Figs. 1 and 2 are on a smaller scale than the other figures.

The drawings represent a motor boat of about forty feet in length and eleven feet wide, propelled by a single engine of the internal combustion type and having sleeping accommodations for ten persons.

Certain features of the invention may be employed in connection with those illustrated or may be utilized in connection with different cabin layouts, especially in the stateroom part.

Referring to Fig. 2, in the embodiment chosen for illustration *a* is the engine room, *b* is the cabin, *c* is the galley or kitchen, *d* the forward stateroom, *e* the lobby and *f* the after stateroom. The engine room *a* is located partly under the bridge deck 1 and partly under the raised deck 2. The cabin *b* and galley *c* are located under the raised deck 2. The two staterooms and lobby are located under the after house 19. As illustrated, each stateroom contains two berths

and a dresser. The lobby contains a companion ladder for entrance from the deck above and communicates with a washroom having the usual plumbing, as shown. The cabin *b* is provided with lockers and two sofas, as shown, and in addition may have hinged upper berths so that four persons may sleep in it. I have illustrated the preferred arrangement of the staterooms and cabin, and I consider it an extremely desirable arrangement, having many advantages, but it is to be understood that certain features of the invention may be employed with a different arrangement of staterooms as well as a different arrangement of galley and cabin.

The bridge deck 1 is utilized as a seating space for the steersman and passengers, and therefore, should be at a lower level than the raised deck 2. A bridge deck so located in relation to the raised deck is highly desirable, because it keeps the weights low, the passengers are protected from wind and spray by the raised deck, the awning is low, and the pitching and rolling movement is less and therefore the comfort to the passengers is greater.

Between the cabin and engine room is a bulkhead 3. This bulkhead is preferably made water and gas tight. It is located forward of the after edge of the raised deck. On the aft part of the raised deck is an erection or house 4. This erection or house extends forward from the bulkhead. Entrance to the cabin is had from the bridge deck by means of the ladder 5 and companion way 6. There is an opening in the raised deck, under the erection 4, through which the ladder extends. This opening extends forward a sufficient distance to allow a person to go down or up the ladder without striking his head against the raised deck. The companion way has the usual slide and doors. The ladder 5 extends from the forward edge of the bridge deck to a point not farther aft than the bulkhead at the point where the latter is intersected by the cabin floor. In order to allow the ladder to go through the bulkhead, the latter is cut away to produce an opening. This opening is at least as wide as the ladder. It extends vertically from the upper edge of the bulkhead to that part of the ladder which protrudes forward through the bulkhead, see Fig. 7.

The depth of the opening will be determined

by the angle of inclination of the ladder, and the width of the side members thereof. On one side of the opening is a hatchway 7, and on the other side is a hatchway 8. Each 5 of these hatchways communicates solely with the engine room. Below each hatchway is an opening 21 through the raised deck 2, see Fig. 3.

It is desirable that the engine room be 10 entirely cut off from the cabin. Means must therefore be provided to inclose the space on each side of the ladder, and the back thereof, so that the engine room will be entirely separated from the cabin in spite of the 15 bulkhead being pierced by an opening. This means is as follows: On each side of the ladder 5 is a panel 9 (see Fig. 7). This panel extends from the bulkhead 3 aft to the ladder and upward from the ladder to 20 the aft edge of the raised deck. On the back of the ladder is another panel 10, this panel being as wide as the opening through the bulkhead 3. These panels 9, 9 and 10 inclose the open space produced by the opening 25 in the bulkhead. The panels 9, 9 may be integral with or separated from the bulkhead. The panel 10 may be secured to the aft inclined edges of the panels 9, 9 or it may be attached to the ladder, or may be a 30 part thereof.

Fig. 9 illustrates a modification in which the panel is integral with the ladder. In this embodiment of the invention the panel is zigzag in longitudinal section, and may be 35 formed of the treads and risers of the ladder, with tight joints.

For the purpose of separating that part 40 of the engine room, which is in the erection, from the cabin, the panels 9, 9 are extended upward to the top of the erection and forward to its front side. These parts of the panels may be integral with the previously 45 described parts which lie in advance of the ladder.

On each side of the erection are windows 50 or ports 11 allowing the entrance of light and air through the openings 21 into the engine room. On the front of the erection are windows or ports 12 admitting light or 55 air to the engine room through the openings 21, 21. Further light and air can be admitted to the engine room through the hatchways 7 and 8 by setting the hatch covers at an angle.

The drawings illustrate a central opening 60 or window 13 communicating with the cabin. This window is desirable, but not necessary. Additional ventilation to the cabin and engine room is secured by means of side ports 14.

Entrance to or egress from the engine room can be made through one of the openings 21, 21 and either of the hatchways 7 or 8 by means of the ladders 15, 15.

65 The engine 16 is located in the center line

of the boat and its flywheel is under the ladder 5. The space between the two bulkheads 3 and 22 (see Fig. 7) determines the length of the engine room. The steering gear 17 and reverse lever 18 are located upon 70 the bridge deck and over the engine room. The reverse lever can extend directly through the bridge deck and by a short and simple connection, such as is illustrated in Fig. 7, can be attached to the reverse gear. 75 The usual gas and spark controls can be arranged close to the steering gear and connected to the engine through very short connections which are not liable to get out of order. The seat 20 on the after house 19 80 allows one person to completely control the boat and at the same time to be seated. The fuel tanks 23 are preferably located as shown within the engine room so that the trim of the boat is not altered by the emptying or filling of the tanks. Berths for the professional crew may be arranged alongside these tanks, as shown folded at 24.

The headroom in the cabin 6 should be at least six feet. The headroom in the engine 90 room a will be the same, through so much as is under the raised deck. Under the bridge deck the headroom will be less, but inconvenience will not exist as the engineer can stand up along one side of the ladder 5, 95 see Fig. 8, and crank the engine, and also make most of the adjustments necessary to run it.

The embodiment of the invention illustrated with the erection or house 4 is considered desirable in vessels of small size. In larger vessels, or where for any reason the erection is undesirable, it may be omitted from the design. In this case the companion way would be directly on the raised 100 deck, and the hatchways 7 and 8 would also be directly on the raised deck. I have illustrated and described the ports or windows 12, 12 as communicating with the engine room, to assist in the lighting and ventilation 110 thereof. This, while highly desirable, is not essential, as the windows or ports may be omitted, or they may not communicate with the engine room.

The ladders 15, 15 may be used under 115 either or both of the hatchways 7 or 8, and if desired but a single hatchway, either 7 or 8, may be used, the opposite side of the companion way being either closed or provided with an opening for light or ventilation, 120 or both.

The raised deck is illustrated in the drawings as extending all the way from the bridge deck to the bow and as wide as the hull, but this deck need not be so long as to 125 extend all the way to the bow and it need not be as wide as the hull.

In accordance with the provisions of the patent statutes, I have described the principle of my invention, together with the 130

apparatus which I now consider to represent the best embodiment thereof; but I desire to have it understood that the apparatus shown is merely illustrative and that 5 the invention may be carried out in other ways.

Having now described my invention, what I claim as new and desire to secure by Letters Patent, is:

10. 1. A motor boat or yacht having a raised deck and a bridge deck behind the same and on a lower level, a cabin entirely under the raised deck, an engine room located immediately aft the cabin and partly under the 15 bridge deck and partly under the raised deck, and separated from the cabin by a transverse bulkhead, there being an opening in said bulkhead, a companion way above the raised deck, a ladder connecting said 20 companion way and cabin and extending through the opening in the bulkhead, said ladder being adjacent to the center line of the hull, an opening in the raised deck on one side of the companion way, and a hatch 25 above said opening.
2. A motor boat or yacht having a raised deck and a bridge deck behind the same and on a lower level, a cabin entirely under the raised deck, an engine room located im- 30 mediately aft the cabin and partly under the bridge deck and partly under the raised deck, and separated from the cabin by a transverse bulkhead, there being an opening in said bulkhead, a companion way above 35 the raised deck, a ladder connecting said companion way and cabin and extending through the opening in the bulkhead, said ladder being adjacent to the center line of the hull, an opening in the raised deck on 40 each side of the companion way, and a hatch above each of said openings.
3. A motor boat or yacht having a raised deck and a bridge deck behind the same and on a lower level, a cabin entirely under the 45 raised deck, an engine room located immedi- 50 ately aft the cabin and partly under the bridge deck and partly under the raised deck and separated from the cabin by a transverse bulkhead, there being an opening in said bulkhead, an erection or house on the raised deck above the bulkhead and lying over both cabin and engine room, a companion way on said erection, a ladder connecting said companion way and cabin and 55 extending through the opening in the bulkhead, said ladder being adjacent to the center line of the hull, an opening in the raised deck on one side of the companion way, a hatchway on the top of said erection and 60 on one side of said companion way, and an engine located within the engine room and lying partly under the ladder.
4. A motor boat or yacht having a raised deck and a bridge deck behind the same and 65 on a lower level, a cabin entirely under the raised deck, an engine room located immedi- 70 ately aft the cabin and partly under the bridge deck and partly under the raised deck and separated from the cabin by a transverse bulkhead, there being an opening in said bulkhead, an erection or house on the raised deck above the bulkhead and lying over both cabin and engine room, a companion way on said erection, a ladder connecting said companion way and cabin and 75 extending through the opening in the bulkhead, said ladder being adjacent to the center line of the hull, an opening in the raised deck on each side of the companion way, a hatchway on the top of said erection and 80 on each side of said companion way, and an engine located within the engine room and lying partly under the ladder.
5. A motor boat or yacht having a raised deck and a bridge deck behind the same and on a lower level, a cabin entirely under the raised deck, an engine room located im- 85 mediately aft the cabin and partly under the bridge deck and partly under the raised deck and separated from the cabin by a transverse bulkhead, there being an opening in said bulkhead, an erection or house on the raised deck above the bulkhead and lying over both cabin and engine room, a companion way on said erection, a ladder connecting said companion way and cabin and 90 extending through the opening in the bulkhead, said ladder being adjacent to the center line of the hull, an opening in the raised deck on each side of the companion way, a hatchway on the top of said erection and 95 on each side of said companion way, and an engine located within the engine room and lying partly under the ladder.
6. A motor boat or yacht having a raised deck and a bridge deck behind the same and on a lower level, a cabin entirely under the raised deck, an engine room located immedi- 100 ately aft the cabin and partly under the bridge deck and partly under the raised deck and separated from the cabin by a transverse bulkhead, there being an opening in the raised deck on each side of the companion way and communicating with said engine room, a hatchway on the top of said erection and on each side of said companion way above said opening in the raised deck, an opening or window on each side of the front of the erection and communicating with the engine room by way of the opening in the raised deck, and an engine located within the engine room and lying partly under the ladder.
7. A motor boat or yacht having a raised deck and a bridge deck behind the same and on a lower level, a cabin entirely under the raised deck, an engine room located immedi- 110 ately aft the cabin and partly under the bridge deck and partly under the raised deck and separated from the cabin by a transverse bulkhead, there being an opening in the raised deck above the bulkhead and extending back to the aft end of the raised deck and lying over both the cabin and engine room, a companion way on said erection, a ladder connecting said companion way and cabin and extending through the opening in the bulkhead, said ladder being adjacent to the center line of the hull, a panel on each side of the ladder extending from the bulkhead aft to the ladder and closing the opening between the ladder and 115
8. A motor boat or yacht having a raised deck and a bridge deck behind the same and on a lower level, a cabin entirely under the raised deck, an engine room located immedi- 120 ately aft the cabin and partly under the bridge deck and partly under the raised deck and separated from the cabin by a transverse bulkhead, there being an opening in the raised deck above the bulkhead and extending back to the aft end of the raised deck and lying over both the cabin and engine room, a companion way on said erection, a ladder connecting said companion way and cabin and extending through the opening in the bulkhead, said ladder being adjacent to the center line of the hull, a panel on each side of the ladder extending from the bulkhead aft to the ladder and closing the opening between the ladder and 125
9. A motor boat or yacht having a raised deck and a bridge deck behind the same and on a lower level, a cabin entirely under the raised deck, an engine room located immedi- 130 ately aft the cabin and partly under the bridge deck and partly under the raised deck and separated from the cabin by a transverse bulkhead, there being an opening in the raised deck above the bulkhead and extending back to the aft end of the raised deck and lying over both the cabin and engine room, a companion way on said erection, a ladder connecting said companion way and cabin and extending through the opening in the bulkhead, said ladder being adjacent to the center line of the hull, a panel on each side of the ladder extending from the bulkhead aft to the ladder and closing the opening between the ladder and 130

bulkhead, and also extending upward to the top of the erection and forward to the front end thereof, a panel on the aft side of the ladder closing the opening occupied thereby, an opening through the raised deck on each side of the ladder, a hatchway in the top of the erection above each of said latter openings, and an opening or window on each side of the front of the erection.

outside of the side panels and communicating with the engine room.

This specification signed and witnessed this 15th day of October, 1914.

MORGAN BARNEY.
